REMOVAL OF WASTE YARN FROM BOBBINS
AND THE LIKEWilliam V. Henry, Candler, N. C., assignor to
American Enka Corporation, Enka, N. C., a
corporation of Delaware

Application July 21, 1949, Serial No. 105,989

4 Claims. (Cl. 28—19)

1

The present invention relates to the removal of waste yarn from holders therefor, and more particularly to a method and apparatus for cutting waste yarn on bobbins, spools and the like that have no rims or flanges on each end.

In the manufacture of rayon, when yarn is unwound from the bobbins a few of the innermost layers are left because they have imperfections which would lower the quality of the finished product when it is sold. The usual method of removing the waste is manually cutting it off by means of a knife, but this method is slow and therefore expensive from a standpoint of production costs. Moreover, the manual cutting operation involves the risk of marring the surfaces of the lacquered bobbins, because it is impossible to regulate with sufficient precision the path of the knife as it passes over the surface of the bobbin.

It is therefore desirable to perform the cutting operation mechanically and with a precision cutter that will sever the convolutions of waste in a clean manner, but without scratching the surfaces of the bobbins. Several such machines have been developed, but they are expensive to build, install and maintain, due to their complicated nature and their multiplicity of moving parts. In all of these machines the bobbins are gripped individually and passed in sequence to a cutter and in a direction transverse to the axis of each bobbin. In other words, the bobbins are positioned side by side with their axes at right angles to the direction of their movement. When each bobbin reaches the cutting zone it must be immobilized long enough for a reciprocating cutting blade to pass across the face of the bobbin and sever the convolutions. This is an intermittent operation requiring all of the bobbins to be held stationary while the one in the cutting zone is being worked on. Such a system is described in U. S. Patent No. 2,303,048.

It is contemplated by the present invention to provide a system in which the waste yarn is automatically severed and removed from the bobbin but the system is characterized by its simplicity and a minimum of moving parts.

Another object of this invention is to continuously feed a plurality of flangeless bobbins arranged in axial alignment one behind the other to a cutting zone and there sever the convolutions of waste yarn with a cutting blade that is stationary in a horizontal plane but pivotal in a vertical plane.

A further object of this invention is to provide an apparatus in which the bobbins are propelled

to the cutting zone by means of two endless conveyor belts.

An additional object of this invention is to propel the bobbins in a horizontal direction in axial alignment until they reach the cutting zone, whereupon the path of travel of each bobbin is deflected for a portion of the cutting operation, but is returned to a horizontal position as the cutting operation is completed on that bobbin.

10 Other objects and advantages of this invention will be apparent from the following detailed description when considered in conjunction with the accompanying drawings, wherein

15 Figure 1 is a top plan view of an apparatus that can be successfully used for continuously advancing the bobbins and cutting the waste therefrom;

20 Figure 2 is a view in side elevation and partial section showing the arrangement of the cutting device and its position with respect to the propelling mechanism;

25 Figure 3 is a view in section taken on line 3—3 of Figure 2;

Figure 4a is a detail partially in elevation and partially in section showing the position of a bobbin which has completely passed through the cutting zone and the position of the next succeeding bobbin with respect to the cutting blade which has begun the initial cutting operation;

30 Figure 4b is a detail partially in elevation and partially in section showing a bobbin that has just passed through the cutting zone and the next succeeding bobbin that has just entered the cutting zone, at which point the cutting blade is in position to begin the cutting operation.

35 Referring to the drawings, flangeless bobbins 10 containing waste rayon are supplied to the right hand side of the machine as viewed in Figures 1 and 2, by any suitable means such as a chute (not shown). These bobbins are propelled in a horizontal direction in axial alignment by means of endless rubber conveyor belts 11 and 12, the bobbins being supported in a V-shaped trough 13, which is mounted on a platform generally indicated at 14. The bobbins 10 bear against the sides of the trough 13 as shown in Figure 3.

40 The endless conveyor belts 11 and 12 are serrated on their exteriors so as to enhance the gripping action between the bobbins and the belts. Each of the endless conveyor belts 11 and 12 pass around a pair of drums 15 and 16, and 45 17 and 18, respectively. Shaft 19 is supported in

bearing 20 and drives drums 15 and 17 by means of suitable gearing (not shown). Mounted on the lower end of shaft 19 is a helical gear 21, which meshes with helical gear 22 which is mounted on a pulley 23. Pulley 23 is, in turn, driven by means of belt 24 passing around a driving pulley 25. Driving pulley 25 is mounted on a shaft 26 driven by any suitable means, not shown.

As the bobbins 10 approach the cutting zone, they pass under a guide roller 27 that is mounted for free rotation on axle 28 which is fastened at each end to uprights 29 and 30. The roller 27 is preferably constructed of rubber which is sufficiently resilient to permit the bobbin passing therebelow to be elevated at its forward end during the cutting operation but sufficiently rigid to hold the bobbin in a horizontal position until the cutting operation has been initiated.

The cutting mechanism consists of a knife 31 fastened through arm 32 to a cross-bar 33 which is mounted for pivotal movement in standards 34. The knife 31 is made integral with a cross-piece 35 which carries springs 36 at each end thereof for urging the knife downwardly. The other ends of springs 36 are attached to posts 37 so that the upward motion of the knife 31 acts against the action of the springs. The downward movement of the knife 31 is limited by stops 38 on each end of cross-piece 35 which engage the upper ends of the respective posts 37. The knife is, therefore, stationary in a horizontal plane but has limited movement in a vertical plane. The shape and general construction of the knife 31 per se forms no part of this invention, except in combination, although it must be adapted for efficient severing of the yarn. One type of knife which has been found to be particularly suitable is that shown and described in U. S. Patent No. 2,098,123.

Referring more particularly to Figures 4a and 4b, each bobbin 10a is conveyed along the trough 13 in a horizontal direction until it is engaged by knife 31, at which point the front end of the bobbin is deflected upwardly by an inclined guideway 39 formed in the trough 13. As the bobbin passes up the guideway the knife 31, being urged downwardly by springs 36, is caused to pass axially of the bobbin from one end to the other and thereby severs the convolutions of yarn. When the cutting operation is completed, the bobbin 10a has reached the position shown in Figure 4b at which point its forward end engages a shoe 40 that forces the bobbin back to a horizontal position, although in a slightly higher plane than it was prior to the cutting operation. It is an important feature of this invention that the knife 31 pass over the rear end of bobbin 10a and drop down to a lower level at the time that the next succeeding bobbin 10b begins its passage up the guideway 39. In this way, it is assured that the knife 31 will not get caught in the rims of the bobbins nor mar the lacquer on the surface thereof.

The shoe 40 is provided with a toe that extends parallel to the bobbin and is urged downwardly by springs 41 which are attached at their lower ends to posts 42 and at their upper ends to a cross-bar 43. Cross bar 43 is integral with shoe 40 which is, in turn, mounted for pivotal movement on bar 44 supported in standards 45. The springs 41 are stronger than springs 36 so that as soon as a bobbin is engaged by shoe 40 as the cutting operation is completed, it will be brought back to a horizontal position just before the knife 31 passes over the end of the bobbin.

After the bobbins containing the severed convolutions of yarn have passed through the cutting zone, they are propelled in their path of travel on the V-shaped trough 13 by the pushing action of each succeeding bobbin. In order to conveniently remove the waste yarn, the bobbins are passed under a water spray 46. In this zone the V-shaped trough is interrupted for about one-third of the length of a bobbin, and as it passes therethrough, the waste yarn falls into a basket 47 provided with a screen bottom 48 in order to allow the water to drain and be carried away by any suitable means.

It can be seen from the above description that the operation of this waste cutter is extremely simple although very efficient. Intricate mechanism for positioning the bobbins and for operating the knife is unnecessary. Feeding the bobbins in axial alignment in a horizontal direction is effected entirely by the conveying belts and the cutting mechanism requires no adjustment so that the entire process is a continuous one which is substantially fool-proof. The spring loaded knife and hold-down shoe maintain the bobbins and knife in relative operative positions at all times while the inclined guideway prevents the knife from getting caught between the bobbins.

What is claimed is:

1. A process for removing waste yarn from flangeless bobbins which comprises arranging a plurality of such bobbins in axial alignment and continuously propelling them in a horizontal direction to a cutting zone, elevating the forward end of each bobbin as it approaches the cutting zone to engage a cutting edge that is stationary in a horizontal plane, severing the convolutions of yarn from below in a path transversely of the bobbins as they are guided through the cutting zone, and returning the bobbins to a higher horizontal position as the cutting operation is completed.

2. Apparatus for removing waste yarn from flangeless bobbins which comprises means for supporting a plurality of such bobbins in horizontal, axial alignment, means for continuously propelling the bobbins to a cutting zone while maintaining this relationship, a cutting mechanism comprising a non-rotary cutting blade that is stationary in a horizontal plane but mounted for pivotal movement in a vertical plane, means urging the blade into contact with the surface of each bobbin as it passes in an axial direction through the cutting zone, means for elevating the forward end of each bobbin as the cutting blade engages and severs the convolutions during the relative transverse movement between the blade and each bobbin, and means to return each bobbin to a higher horizontal position as the cutting operation is completed on that bobbin.

3. Apparatus for removing waste yarn from flangeless bobbins which comprises means for supporting a plurality of such bobbins in horizontal, axial alignment, conveying belts for continuously propelling the bobbins to a cutting zone while maintaining this relationship, a cutting mechanism comprising a non-rotary cutting blade that is stationary in a horizontal plane but mounted for pivotal movement in a vertical plane, spring means urging the blade into contact with the surface of each bobbin as it passes in an axial direction through the cutting zone, means for elevating the forward end of each bobbin as the cutting blade engages and severs the convolutions during the passage

of the bobbin through the cutting zone, and a spring loaded shoe for returning each bobbin to a horizontal position at a higher level as the cutting operation is completed.

4. Apparatus for removing waste yarn from flangeless bobbins which comprises a V-shaped trough for supporting a plurality of such bobbins in horizontal, axial alignment, conveying belts on each side of the bobbins for continuously propelling them to a cutting zone while maintaining this relationship, a cutting mechanism comprising a non-rotary cutting blade that is stationary in a horizontal plane but mounted for pivotal movement in a vertical plane, spring means urging the blade into contact with the surface of each bobbin as it passes in an axial direction through the cutting zone, an inclined guideway for elevating the forward end of each bobbin as the cutting blade engages and severs the convolutions during the passage of the bobbin through the cutting zone, and a spring

loaded shoe for returning each bobbin to a horizontal position at a higher level as the cutting operation is completed.
